CLAIM

We claim the ornamental design for a dispenser nozzle, as shown and described.

DESCRIPTION

FIG. 1 is a perspective view of the dispenser nozzle.

FIG. 2 is a right elevation view of the dispenser nozzle of FIG. 1.

FIG. 3 is a left elevation view of the dispenser nozzle of FIG. 1.

FIG. 4 is a rear elevation view of the dispenser nozzle of FIG. 1.

FIG. 5 is a front elevation view of the dispenser nozzle of FIG. 1-FIG. 4.

FIG. 6 is a top view of the dispenser nozzle of FIG. 1-FIG. 5; and,

FIG. 7 is a bottom view of the dispenser nozzle of FIG. 1-FIG. 6.

The broken lines shown in FIG. 4 shows a portion of the dispenser nozzle that forms no part of the claimed design.
